(57) **CLAIM**

We claim the ornamental design for a display screen or portion thereof with icon, as shown and described.

DESCRIPTION

FIG. 1 is a front view of a display screen or portion thereof with icon in accordance to a first embodiment showing our new design; and,

FIG. 2 is a front view of a display screen or portion thereof with icon in accordance to a second embodiment showing our new design.

The outermost perimeter illustrated by a pair of dashed broken lines illustrate a display screen or portion thereof and forms no part of the claimed design.

The graytones shown in the drawings illustrate a contrast in appearance.

1 Claim, 2 Drawing Sheets
